UNITED STATES PATENT OFFICE.

HAROLD J. STEAD, OF GENEVA, NEW YORK.

BIFOCAL-LENS BLANK.

Application filed March 23, 1921. Serial No. 454,627.

To all whom it may concern:

Be it known that I, HAROLD J. STEAD, a citizen of the United States, of Geneva, in the county of Ontario, in the State of New York, have invented new and useful Improvements in Bifocal-Lens Blanks, of which the following, taken in connection with the accompanying drawings, is a full, clear, and exact description.

10 This invention relates to certain improvements in bifocal lens blanks and the tools and process for producing the same.

So far as I am aware, practically all commercial one piece bifocal lens blanks furnished to the trade embody two ground and polished optical fields of different dioptrics upon one side of a piece of glass.

It will be obvious that with a blank of that character in which the relation of the 20 bifocal surfaces is fixed as to curvature, the prescription lens grinder, in order to produce the multitude of prescriptions prescribed for various degrees of eye defects, must have a large stock of blanks in which 25 the relative curvature of the bifocal surfaces differ, and must have a large quantity of grinding tools for finishing the rough side of the blank.

These tools usually have a different base 30 curve, or combination of curves, which in combination with the already finished side of the bifocal blank, form a finished lens according to prescription.

These tools cost approximately \$1.00 each, 35 and there are upwardly of three hundred of them required to produce the general run of prescriptions. There would be an infinitely large number of them required to fill all 40 prescriptions (many thousands of lens combinations) and the fact that these tools are essential to the finishing of the present one-piece bifocal blank has seriously retarded the commercial development of that product.

45 My invention consists primarily in a bifocal lens blank having the reading field only finished. This reading field, or section, is formed as a circular field in the center of a large lens blank, and is depressed beneath 50 the surrounding surface. My experiments have demonstrated that a relatively small circular field can be molded to accurate curvature, and will not require additional labor such as grinding and polishing in order to 55 adapt it perfectly for visual purposes.

The blank of this invention, therefore, has the central or reading section molded to an accurate curve suitable for commercial purposes without grinding or polishing. The balance of this side of the blank, as well as 60 the opposite side of the blank is moulded to a general curvature, but not with any idea of doing so perfectly.

By forming only the reading section in condition for visual purposes, leaving the 65 distance section rough and the opposite side of the blank rough, a tremendous saving is effected not only as to the original equipment required by the dealer, but also a saving in constant up-keep. This together with 70 the small number of blanks which the dealer would be required to carry in stock covering a certain range of lens prescriptions, means considerable to the dealer. When the dealer is ready to grind, or does grind both sides 75 of a bifocal lens blank, he may do so with the ordinary grinding tools in common use. Therefore, it is an extreme advantage to give to the dealer a bifocal blank which he can 80 finish to prescription by grinding both sides 85 to any focal power that might be called for, with the ordinary grinding tools in common use.

With the central or reading section molded perfectly, the outer section is then ground 85 and polished in the usual manner with ordinary lens-grinding machinery, and the tools now in general use. This work can be done by the dealer, when a required prescription is presented. Or the manufacturer may, as 90 a step in production, grind this outer, or distance surface to any pre-determined curvature desired. The only precaution necessary in performing that operation is not to 95 grind too far so that the central or reading field would be touched by the grinding tool with which the outer or distance surface is being ground. This necessarily would form a vertical shoulder separating the reading and distance fields, which shoulder would 100 vary in height in different prescriptions, according to the difference in curvature between these two fields.

The blank so formed with the reading section molded to an accurate curvature, may, 105 as illustrated, be approximately three inches in diameter, and the moulded reading field may be approximately 32 mm. in diameter, permitting the lens blank to be cut in half, 110 each half forming a single bifocal lens.

However, preferably the reading section would be formed about 19 mm. in diameter, and a single lens blank would be cut from the large blank in such manner that the 19 mm. reading field would be at one edge of the blank when cut out.

This depressed reading field may be molded upon either the concave or convex side of the blank, and the balance of the blank is left rough, so that the dealer can finish it as he wishes with the ordinary tools commonly used in lens grinding establishments.

Other objects and advantages of the invention will more fully appear from the following description, taken in connection with the accompanying drawings, in which:

Figure 1 is a sectional view of a mold section and a glass blank supported thereby.

Figure 2 is a similar section after the glass has conformed itself to the mold section.

Figure 3 is a section illustrating the method of molding the bifocal side of the blank.

Figure 4 is a face view of the completed blank.

Figure 5 is a modification of the mold, showing the bifocal surfaces as molded upon the concave side of the blank.

The surface of the glass blank —1— upon which the reading field is to be molded should first be polished. It is not necessary to polish the entire surface, but only that portion which is to form the reading surface. This surface is then thoroughly cleansed and rendered free from all foreign material, and is placed on a form or mold section —2—, which may be composed of any suitable refractory substance that will impart to the glass the general curvature required on the side of the blank opposite the bifocal side.

The blank is covered with any suitable cover, as a porcelain cover, or one made of any material which will not oxidize or scale and permit falling particles to drop upon the surface of the glass which is to form the reading field. This assembly, including the mold section —2—, the glass blank —1— and the suitable cover, is placed in a furnace, heated in any suitable manner, as by gas or electricity, and to a temperature sufficient to heat and cause the glass to subside and conform generally to the mold section —2— upon which it is resting.

When the glass has reached a proper molding temperature, the assembly is withdrawn from the furnace, the glass blank —1— uncovered, and it is then placed in a press directly beneath the die or mold —3— which is to form the bifocal surface, and in the usual pressing manner the die is forced downwardly on the glass blank to shape the upper surface thereof into a counterpart of the die, or mold section —3—.

The mold sections —2— and —3— form-

ing the surfaces are to be shaped approximately to a desired curvature, and may be made of any suitable material, such as cast-iron, which is usually employed in making molds for glass. That part of the mold, however, which is to form the reading section and which is to be molded to an accurate curvature, should be of a material which is of infinitely fine grain or texture, and that will accept on its surface a very high finish or polish substantially the same as glass. This is necessary so that the surface of the glass formed by this mold section shall be an exact counterpart of the surface of this part of the mold itself. For this purpose the mold section —3— is preferably formed in two parts.

The main portion of the same, and which is adapted to shape the distance field of the blank to a generally accurate curvature is of annular form, and may, as heretofore stated, be formed of cast-iron or other suitable material. A section —5— adapted to mold the reading field to an accurate curvature is removably inserted within the central recess of the annular body —6— of the mold section —3—. This part —5— is of such size and form as to tightly fit within the annular part —6— and preferably projects somewhat below the molding surface of the part —6— so that the reading field when molded by the mold section —3— lies below the surface of the distance portion of the blank as molded by the annular part —6—. In other words, the reading field, when completed, is depressed beneath the general contour of the blank. This permits the distance field —8— of the blank to be ground by the ordinary grinding tools without special precaution, care being taken only to stop the grinding of the distance field before the grinding tool comes into contact with the depressed reading surface —9—.

The glass so molded is then placed in an oven and subjected to an increased temperature to fire polish the surface of the reading section. Then the blank is gradually cooled. That part of the mold forming the reading section may be changed from time to time according to the curvature desired to secure different bifocal additions.

In Figure 4 the completed blank is shown and the circle —7— indicates the commercial blank to be cut therefrom. However, as above stated, the reading surface may be of sufficient diameter to permit its utilization in the formation of two bifocal lens blanks. This will be effected by merely splitting the blank when completed and utilizing each half in the manufacture of a single lens.

In Figure 5 a reverse condition is shown in that the reading field is molded upon the concave side of the blank. In other respects the construction is the same.

It is essential that the part 5 of the mold

section —3— should be formed of a suitable material so as to produce an accurately sub-molded surface which will not require subsequent grinding or polishing.

5 I have found that the metal nickel and the alloys known as Monel and Invar are suitable for my purpose. However, there may be various other materials equally as well suited and perhaps more efficient for 10 the purpose, and I do not desire to limit myself to these particular substances for the formation of the die parts to shape the reading field. Further, when desired, the entire mold section —3— may be formed 15 of one integral piece of the metal such as nickel found most satisfactory for molding the blank to accurate curvature suitable for visual purposes without grinding or polishing in the usual manner. Altho it may be 20 desirable in certain cases to slightly polish the surface after molding and by "finished visual surface", as used in the claims of this application, I mean such a molded surface as is suitable for visual or optical purposes 25 without additional grinding, altho some polishing may be desirable.

Although I have shown and described a specific form and construction of lens blank, and have set forth in detail a perhaps preferred method of manufacturing the same, I 30 do not desire to limit myself to the details of either the product or the process except as the same may be specifically set forth in the claims hereto appended.

35 What I claim is:

1. A lens blank having upon one face a relatively small depressed central portion molded to an accurate curvature suitable for visual purposes without grinding or polishing, and a relatively large surrounding surface molded to an approximate curvature, and the other face of the blank molded to an approximate curvature.

2. A lens blank having upon one face a 45 relatively small portion molded to an accurate curvature suitable for visual purposes without grinding or polishing, and a relatively large portion shaped to an approximate curvature and surrounding the relatively small portion.

50 3. A bifocal lens blank having a relatively

small center portion molded to an accurate curvature suitable for visual purposes without grinding.

4. A bifocal lens consisting of a piece of 55 glass having one surface ground and polished to an accurate curvature, the opposite surface having a distance field ground and polished to an accurate curvature and a near field molded to an accurate curvature and 60 separated from the distance field by an intervening shoulder.

5. A bifocal lens having a near field molded to an accurate curvature suitable 65 for visual purposes without grinding, and depressed beneath the adjacent field.

6. A bifocal lens consisting of a piece of glass having one surface ground and polished to an accurate curvature, the opposite surface having a distance field ground and 70 polished to an accurate curvature and a near field molded to an accurate curvature suitable for visual purposes without grinding.

7. A bifocal lens blank having a relatively small portion molded to an accurate 75 curvature suitable for forming the near vision portion of a bifocal lens without grinding, and a comparatively large adjacent integral portion adapted to form the distance vision portion of said bifocal lens. 80

8. A bifocal lens blank having a relatively small portion molded to an accurate curvature suitable for forming the near vision portion of a bifocal lens without grinding, and a comparatively large adjacent integral portion adapted to form the distance vision portion of said bifocal lens, the latter portion being raised above the former.

9. A bifocal lens blank having a relatively small portion molded to an accurate curvature suitable for visual purposes without grinding, and an adjacent integral portion of larger size adapted to form the distance visual portion of a bifocal lens.

In witness whereof I have hereunto set my hand this 10th day of Mch. 1921.

HAROLD J. STEAD.
